UNITED STATES PATENT OFFICE.

ALBRECHT VOGT, OF ROCHESTER, NEW YORK.

DESIGN FOR A BURIAL-CASKET HANDLE.

SPECIFICATION forming part of Design No. 15,033, dated May 27, 1884.

Application filed December 26, 1883. Term of patent 7 years.

To all whom it may concern:

Be it known that I, ALBRECHT VOGT, of Rochester, Monroe county, New York, have invented or produced a new and original Design for Burial-Casket Handles; and I do hereby declare that the following is a full, clear, and exact description of the same, reference being had to the accompanying drawings, in which—

10 Figure 1 is an elevation of one end of the handle. Fig. 2 is a cross-section of the same.

My new design relates to casket-handles covered with a platted or braided covering. The design consists of such a handle polygonal in cross-section and provided with ornamental ends, as hereinafter described.

In the drawings, A shows one end of the handle, the other end being broken off, but of the same form. In cross-section the handle 20 is polygonal, as shown. a is the plating or braiding, which is crossed, presenting an or-

namental appearance. b b are beads or moldings at the end. c is a beveled body or cone, and d is a round extremity. These parts form the end, which is of larger diameter than the 25 body. The whole presents a highly-ornamental appearance.

What I claim as new, and desire to secure by Letters Patent, is—

The design herein described, consisting of a 30 burial-casket handle having a polygonal body with a platted covering, and ends provided with beads b b, cone c, and round end d, as herein shown and described.

In witness whereof I have hereunto signed 35 my name in the presence of two subscribing witnesses.

ALBRECHT VOGT.
